CUFF LINK

Lester Douglas Burr, Jr., Foxboro, Mass., assignor
to R. F. Simmons Company, Attleboro, Mass., a
corporation of Massachusetts

Application July 9, 1946, Serial No. 682,272

3 Claims. (Cl. 24—97)

1

This invention relates to cuff-links or cuff-buttons and consists in a novel and improved construction therefor. The present device may comprise a fixed ornamental head with a shank or post projecting at right-angles thereto and a pair of cross-members pivoted to the upper end of the post to adapt them to be rocked into alignment therewith for insertion through the button-holes of a cuff and to be thereafter turned at right-angles or normal to the post to hold the parts of the cuff together.

One object of the invention is to provide an improved mounting for the pivotal members at the end of the post with resilient means contained therein for yieldably retaining the cross-members in either position to which they may be turned.

Another object is to provide a cuff-link or cuff-button of the type indicated having a hollow post formed of folded complementary sections with a pair of cross-members pivoted at its outer end, bearing elements within the post engaging the pivot of the cross-members and a novel type of spring for actuating said bearing members to control the swinging or rocking motion of the cross-members.

Another object is to provide a cuff-link or cuff-button of the type indicated having a tubular post with a transverse opening at its end for receiving a pintle or pivot provided with flat faces on its sides, cross-members mounted on the ends of the pivot at the sides of the post, bearing elements engaging the pivot, and a corrugated or multi S-shaped spring acting to press said bearing elements together to control the turning movement of the pivot and thereby the rocking motion of the cross-members.

Further objects of the invention are set forth in the following specification which describes a preferred form of construction of the improved cuff-link or cuff-button as illustrated by the accompanying drawing.

In the drawing:

Fig. 1 is a perspective view of the present improved cuff-link or cuff-button;

Fig. 2 is a side elevation of the same, part-sectional through a portion of its ornamental head and showing one of the cross-members as removed from its pivot on the post;

Fig. 3 is a vertical sectional view of the cuff-link taken in a plane common to the longitudinal axis of its post;

Fig. 4 is a similar sectional view looking in a direction opposite to that of Fig. 3;

Fig. 5 is a detailed view of the hollow post of 55 their sides or flanges 15 in abutting relationship

2

the cuff-link or button showing it as partly formed; and

Fig. 6 is a vertical view of a modified form of the cuff-link taken in a plane common to the axis of its post and showing another form of construction of the bearing elements which control the pivotal movement of the cross-members.

Various types of cuff-links or cuff-buttons comprising a fixed head with a post projecting therefrom and a cross-member or members pivoted to its end have heretofore been used in the art. Most of these prior devices, however, have not been of ornamental or artistic appearance due to the fact that the mechanical elements for controlling the pivotal movement of the cross-members at the ends of the post have been conspicuously exposed to view and subject to interference and distortion to render them impractical and unreliable in use. The present invention 10 contemplates a form of construction in which the shank or post of the cuff-link or button is of tubular form with a pair of cross-members pivoted at its outer end and novel resiliently-operated means are enclosed within the post so 15 that all the mechanical elements are entirely 20 concealed from view and protected against disarrangement.

In the present drawing Fig. 1 illustrates the improved cuff-link or button as comprising a fixed head 2 which may be of ornamental configuration and a hollow shank or post 3 projecting centrally therefrom. A pair of cross-members 4, herein shown as of substantially lenticular shape, are pivoted to the end of the post 3 abutting the opposite sides thereof to adapt them to be normally held in position at right-angles thereto or to be rocked or turned into alignment therewith as indicated by the dash-lines in Fig. 2.

The head 2, shown as of circular outline, is 30 preferably constructed from sheet-metal stamped out with a cupped base-portion 5, to which is joined a substantially flat disk-like plate 6 having its marginal portion 7 shaped to interfit and engage with the cupped rim 8 of the base. The central portion of the plate 6 may be crowned 35 slightly as shown at 9 and formed with a slot 10 for receiving a pair of lugs 10 projecting from the bottom of the post 3, a permanent connection being made between the post and the head 40 by soldering or other means. The post 3 is preferably constructed from a channel-shaped strip, see Fig. 5, which is cut away at the center to adapt it be bent or folded into two legs 14. When the legs 14 are brought together with the edges of 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

as shown in Fig. 2, a tubular member is provided having one end closed and the lugs 10 adapted to be inserted through the slot 16 in the plate 6 of the head 2 and soldered thereto. Oppositely-disposed pointed prongs 17 at the ends of the tubular post 3 are bent at right-angles as shown in Figs. 4 and 6 to form a step or holding means for a spring 26 to be later described.

The two cross-members 4 which form the outer head of the cuff-link or button are mounted fast on the end of a pintle or pivot 21 which projects through circular holes 22 in the sides of the post 3; it being noted by reference to Fig. 5 that the holes 22 are formed by semi-circular recesses in the flanges of the two legs 14 of the channel strip. The cross-members 4 may be fixedly secured to the ends of the pivot 21 and the latter then inserted into the recesses in the flanges of the legs 14 before the legs are bent close together with their edges in abutting relationship.

As before indicated, the turning movement of the cross-bars or members 4 is controlled by a pair of bearing elements engageable with the square-shaped pivot 21 and acted upon by a spring 29 enclosed within the post 3. As shown in Fig. 3 a bearing block 24 of relatively hard or tempered metal is placed within the hollow post 3 seated against its closed end, this element being inserted in the end of the post before the pivot 21 is placed in the holes or openings 22 in the sides of the post. A second somewhat larger bearing element or block 25 is inserted into the hollow of the post 3 after the pivot 21 is in place and thereafter the spring 20 is introduced into the hollow of the post to adapt it to bear against the end of the larger block 25, with its lower end seated on and supported by the prongs 17 at the foot of the post. The spring 20 is preferably of a novel shape as shown in Fig. 3, that is, it is constructed of a relatively wide and comparatively thick strip of hardened metal corrugated to form oppositely-extending loops 26 and 27. In other words, it may be comprised of a plurality of S-shaped sections formed from a continuous strip. It will be apparent that with the spring 20 held under tension within the post 3 with one end seated on the prongs 17 and its opposite end bearing against the larger block 25, it will exert pressure tending to slide the block toward the bearing element 24 to resist the turning movement of the pivot 21 and cross-members 4. As shown in Fig. 3 the two bearing elements 24 and 25 may be formed with slight depressions or V-shaped notches 28 and 30 adapted to be engaged by the sharp corner-edges of the rectangularly-shaped pivot 21 to restrain the latter against turning movement in the holes 22. As shown in Figs. 2 and 3, the pivot 21 is disposed at an angle of ninety degrees with respect to the longitudinal axis of the cross-members 4 so that the diagonally-arranged edges of the pivot 21 engage with the notches 28 and 30 to maintain the cross-members 4 in normal position relatively of the post 3.

When it is desired to insert the cuff-link through the button-holes of a cuff, the cross-members 4 may be turned into the position indicated by the dash-lines in Figs. 2 and 3 to align them with the post 3, thereby providing for an easy entrance of the post through the button-holes due to the tapered contour of the cross-members. During this turning movement or rocking of the cross-members 4 the edges of the pivot 21 will be caused to ride out of the notches 28 and 30 as the bearing element 25 is slid downwardly in the post 3 against the tension of the

spring 20. It is obvious that during the rocking of the cross-members 4 and the sliding action of the bearing element 25 as it recedes from the opposite bearing element 24 the pivot 21 must be displaced slightly, that is moved toward the fixed head 2 of the button and this is provided for by forming the holes 22 in the sides of the post large enough to insure a clearance around the edges of the pivot. If desired, the holes 22 may be made slightly elongated or elliptical in shape with the major axis coinciding with the longitudinal axis of the post.

In the form of construction shown in Fig. 6 of the drawing, the bearing elements 31 and 32 have straight or planar faces for engagement with the flat sides of the rectangular pivot 21. In this embodiment of the invention the pivot is disposed with two of its flat sides parallel to the longitudinal axis of the cross-members 4 so that the bearing members normally maintain the members in the position illustrated in Fig. 6, or normal to the axis of the post 3. When the cross-members 4 are turned into alignment with the post 3 the opposite square sides of the pivot 21 will be engaged by the straight sides of the bearing elements 31 and 32, thus operating to yieldably hold the cross-members in either position to which they may be adjusted.

It will be observed from the foregoing specification that the present invention provides a novel and ingenious construction for cuff-links and cuff-buttons which results in considerable improvement in the art. By the use of the bearing elements engaging with the pivot of the cross-members at the end of the post, said cross-members are held in their different positions yieldably yet with considerable resistance against accidental or unwarranted turning of the members either before being inserted through the cuff or after having been adjusted to hold the button in place. The present novel form of spring used for resiliently operating the bearing members possesses considerable improvement over other types, such as helical wire springs, due to the fact that it can be made of more substantial material, that is, of considerable width and thickness so that it will not lose its tension under repeated flexing or compression. As a further feature of improvement, the bearing elements engaging against the pivot tend to prevent any play or back-lash in the latter so that the cross-members are maintained substantially rigid in whatever position to which they are adjusted without undue looseness. The present improved cuff-link or button further is of more ornamental and attractive appearance due to the fact that all of its mechanical elements are enclosed and concealed from view, thereby also tending to prevent interference therewith and derangement thereof during the use of the article.

While the present improved cuff-link or button is herein shown and described as embodied in only two preferred forms of construction, it is to be understood that various further modifications may be made in the form and arrangement of its parts without departing from the spirit or scope of the invention as expressed in the following claims. Therefore, without limiting myself in this respect, I claim:

1. A cuff-link comprising a head, a hollow post projecting from said head, said post constructed of sheet-metal formed to U-shape in cross-section and folded at the center to provide two legs arranged with the edges of their side flanges abutting and connected by a cross-strip providing

a closure at one end, a circular opening formed in the opposite folded sides of the post, a pivot-pin projecting through said opening to adapt it to rotate therein, said pivot-pin being of rectangular shape in cross-section, a pair of cross-members fastened to the ends of the pivot-pin to adapt them to assume a position normal to the post and to be turned into alinement therewith for insertion through the buttonholes in a cuff, a plate-like member in the closed end of the post abutting the cross-strip, a block slidable in the post on the opposite side of the pin from the plate, and a spring tensioned in the post beneath the block to force it against the pivot-pin to normally retain the cross-members in either position to which they may be turned.

2. A cuff-link or cuff-button comprising a head, a hollow post projecting from the head, said post constructed of sheet-metal bent into U-shape in cross-section and folded at the center to provide two opposed sides arranged with the edges of their lateral flanges in abutting relationship to provide a tubular structure closed at one end by the cross-strip of metal connecting the two sides of the post, a circular opening in the sides of the post at the closed end thereof formed by semi-circular perforations in the abutting flanges of its sides, a plate held in the closed end of the post abutting the cross-strip joining its sides, a pivot-pin of rectangular shape in cross-section projecting through the opening in the sides of the post and rotatable therein to adapt one of its flat sides to engage the inner face of the plate, a block slidable in the post and adapted to engage an opposite flat side of the pivot-pin, a spring in the post constructed of a flat strip of metal bent into serpentine form with a plurality of

U-shaped lobes, said spring fixed at its lower end with its opposite end held under tension engaging against the block to slide the latter to engage it with a side of the pivot-pin, and a pair of cross-members mounted on the ends of the pivot-pin to adapt them to extend at right-angles to the post with the slidable block and plate engaging opposite sides of the pivot-pin to yieldingly hold the cross-members in different positions of adjustment, said cross-members being manually rotatable with the pin to aline them with the post as the spring yields to allow the block to slide to release the pivot-pin.

3. A cuff-link or cuff-button as described in claim 1 wherein the plate at the end of the post and the slidable block are each formed with V-shaped notches for engaging the edges of the rectangular pivot-pin to hold the cross-members in either normal relation to the post or rocked into alinement therewith.
